DIAPHRAGM UNIT

Lloyd Hornpostel, Beloit, Wis., assignor to Beloit
Iron Works, Beloit, Wis., a corporation of Wisconsin

Application July 30, 1945, Serial No. 607,728

5 Claims. (Cl. 267—1)

1
This invention relates to a diaphragm unit, and more particularly to a diaphragm unit for use with a roll assembly in a paper making machine in which the amount of pressure mechanically applied to maintain the desired amount of pressure contact between the rolls acts through and is controlled by a gaseous fluid actuated diaphragm.

Heretofore it has been customary to control the amount of pressure contact between press rolls and the like by the use of pressure applying mechanisms acting through resilient means, such as springs. Such mechanical pressure applying mechanisms, however, are difficult to so control and operate as to maintain the desired pressure contact uniformly along the line or area of contact between the rolls. It is also difficult to re-set such mechanical pressure loading devices at the same pressure, or at some other desired pressure, when starting up again on a run of the same weight and grade of paper, or of a different weight and grade of paper. Inasmuch as the strength and other characteristics of the paper web depend quite largely upon the maintenance of the proper degree of pressure loading between the press rolls or other pressure contact rolls between which the web is to be passed, it is highly important that the proper amount of pressure be maintained at all times during the operation of the machine.

In accordance with the principles of my present invention, I provide a pressure loading mechanism that includes a mechanically operated pressure applying device, such as a hand or power operated jack, and a gaseous fluid operated diaphragm through which the mechanically operated device applies pressure to the movable roll of the roll assembly. In the operation of my fluid pressure controlled roll assembly the diaphragm is pre-loaded to the desired extent and then the mechanically operated pressure applying mechanism is operated, either manually or by power means, until the amount of the pre-loading on the diaphragm is being transmitted to the movable roll of the assembly. In order to determine that this is the case, the gaseous fluid actuated diaphragm is provided with indicating means for indicating to the operator that the diaphragm is in the pre-determined, or normal, position at which exactly the amount of the preloading on the diaphragm is being transmitted to the roll assembly. In this way the loading pressure on the rolls of the assembly can be controlled very exactly and can be varied at will.

It is therefore an important object of this invention to provide a diaphragm unit for use in

2
a fluid pressure controlled roll assembly in a paper making machine, or other fabric processing machine, in which diaphragm unit means including axially deflectable members are provided for imparting lateral stability to the unit without substantially resisting axial movement of the diaphragm itself.

Other and further important objects of this invention will be apparent from the disclosures in the specification and the accompanying drawings.

As shown on the drawings:

Figure 1 is a schematic showing in side elevation of a portion of a paper making machine in which are installed a plurality of fluid pressure controlled roll assemblies embodying the principles of my invention.

Figure 2 is a fragmentary enlarged elevational view of the double diaphragm device used in the 20 felt press roll assembly illustrated in Figure 1.

Figure 3 is a top plan view of the double diaphragm device of Figure 2.

Figure 4 is an enlarged sectional view taken substantially along the line IV—IV of Figure 2, 25 with parts in elevation and broken away.

Figure 5 is an enlarged sectional view taken substantially along the line V—V of Figure 1.

Figure 6 is a sectional view taken substantially along the line VI—VI of Figure 5.

Figure 7 is a fragmentary sectional view taken substantially along the line VII—VII of Figure 5.

In Figure 1, the reference numeral 10 indicates generally the large drier drum of a Yankee type paper making machine, a portion of one side frame of which is indicated by the reference numeral 11. Each side frame 11 includes upright frame members 12 and 13 supported upon a flooring 14, and a horizontal frame member 15 supported by said upright frame members 12 and 13. 35 It will be understood that the showing in Figure 1 is schematic only.

Schematically shown are a couch roll 16, over which the forming wire 17 travels, and a lower roll 18 for the return of the under span 19 of said wire 17. The upper span of said forming wire 17 carries the web of fibrous material formed thereon into contact with a top press felt 20 that is held by means of a pressure roll 21 against the wire 17. The wet fibrous web is thus picked up by the felt 20 as the felt passes through the nip between the rolls 21 and 16, and is carried by said felt into the first press roll section, indicated generally by the letter P.

Said first press roll assembly P includes an upper movable press roll 22 and a lower stationary

suction press roll 23. A bottom press felt 24 is trained through the nip between the rolls 22 and 23 of the first press roll assembly P. Felt guide rolls 25, 26 and 27, and felt press rolls 28, 29 serve to guide the lower press felt 24 through a pre-determined path.

After passing through the first press assembly P, the top press felt 20, with the wet web carried on the under surface thereof, passes around a guide roll 30 into the nip between a lower pressure transfer roll 31 and the large Yankee drier 10. The moist web is transferred from the felt 20 by means of the pressure transfer roll 31 to the highly polished surface of the Yankee drier drum 10. As the drum 10 revolves with the paper web in contact therewith, the paper web is dried, or partially dried, and is then stripped from the surface of said drum for further processing. As shown, the paper web W is stripped from the surface of the Yankee drier drum 10 by means of a creping doctor 32, but the particular manner of stripping the web W from the surface of the roll forms no part of the present invention.

After leaving the nip between the pressure transfer roll 31 and the drier drum 10, the felt 20, now bare, passes under and over guide rolls 33 and 34 and into a felt press assembly, indicated generally by the letters FP. The purpose of this press assembly is to extract water from the felt before it returns to the nip between the couch roll 16 and the pressure transfer roll 21. After leaving the press roll assembly FP, the felt 20 is guided by means of guide rolls 35, 36, 37, and 38 back to the pressure transfer roll 21.

It will be noted that each of the press roll assemblies P and FP, as well as the roll assembly including the pressure transfer roll 31 and the Yankee drier drum 10, includes a device for maintaining pressure between the movable roll and the stationary roll of each of these assemblies. The pressure applying mechanisms are indicated by the letter M in the first press roll assembly P; by the letters TM in the transfer roll-drier drum assembly; and by the letters FM in the felt press assembly FP. These various pressure applying mechanisms will later be described with greater particularity.

The felt press assembly FP comprises a lower suction press roll 39 mounted upon the side frame members 15 and an upper movable plain press roll 40 supported at its ends by pivotally mounted arms 41. Each of said arms 41, of which only one is shown, is mounted at one of its ends by means of a pivot pin 42 from a support 43. The ends of said upper plain press roll 40 are journaled in bearing brackets 44 depending from the under sides of said pivotally mounted arms 41. The other end of each said arms 41 extends beyond the bearing brackets 44 and is bifurcated, as at 45 (Figs. 1, 2 and 4).

As best shown in Figures 2 and 4, the bifurcated end 45 of each of said arms 41 is formed with an apertured cylindrical portion 45a for receiving a pin 46 connecting said arm to the central hub portion 47 of a double diaphragm mechanism, indicated generally by the reference numeral 48. Cotter pins 49 pass through the extended ends of said pins 46 to hold the pins in place. The pins 46 thus provide a swivel mounting between the bifurcated ends 45 of the arms 41 and the hub portions 47 of the diaphragm mechanisms 48.

Said diaphragm mechanisms 48 have pressure transmitting rods 50 connecting them with mechanically operated jacks 51 (Fig. 1).

Each of the jacks 51 has a manually operable crank arm or handle 52 for turning a shaft 53, the inner end of which extends into a casing 54 and carries a pinion (not shown) for meshing with a pinion or worm on the lower end of the connecting rod 50. Instead of providing for manual operation of the shaft 53, said shafts 53 may be connected to suitable power means for operating the jacks 51. The detailed operation of the jacks 51 will be obvious from the foregoing description to anyone familiar with such mechanisms.

As best shown in Figures 2 to 4, inclusive, each of the diaphragm mechanisms 48 includes a frame comprising a pair of upper and lower straps 48a and 48b, respectively, the ends of which are joined together by means of adjustable tie rods 48c and 48d. Said tie rods 48c and 48d are threaded at their ends for reception into internally threaded end sockets 55 and 56, respectively, formed on said straps 48a and 48b. Nuts 57 and 58, and 59 and 60 are provided for securing the ends of said rods 48a and 48b within said end sockets 55, 55 and 56, 56. The straps 48a and 48b, and the tie rods 48 and 48d, thus form a rigid frame.

The upper strap 48a has a central enlargement 61 from which depends an integral circular plate 62. The central portion of a diaphragm 63 is clamped against the under side of said circular plate 62 by means of a smaller circular plate 64 and screws 65. The outer periphery of said diaphragm 63 is clamped against the upper surface of a peripheral flange 66 of a downwardly concave casing member 67 by means of a ring 68 and screws 69. Said diaphragm 63 thus forms the upper wall of a chamber 70 within the concavity of the casing member 67. A pipe 71 serves for the admission of a gaseous fluid under pressure into said chamber 70. The lower plate 64 and the inner wall of the casing member 67 are provided with normally spaced, aligned abutments 72 and 73, respectively, for the purpose of limiting the relative movement toward each other of said diaphragm 63 and casing member 67.

The said casing member 67 is integrally connected through webs 74 and 75 to the hub portion 47 between the previously described bifurcated ends 45, and by continuations of said web portions to a casing member 76 forming a part of the lower diaphragm portion. Said casing member 76 is upwardly concave and formed with a downwardly extending annular flange 77, against which is clamped a diaphragm 78 by means of a ring 79 and screws 80. Said diaphragm 78, like the diaphragm 63, is formed of suitable flexible, resilient material, such as a natural rubber or synthetic rubber composition or the like.

The central portion of said diaphragm 78 is clamped between an upper circular plate 81 and a lower, larger circular plate 82 by means of screws 83. The upper plate 81 and the inner surface of the casing member 76 are provided with opposed aligned abutments 84 and 85, respectively. These abutments serve to limit relative movement toward each other of the casing member 76 and diaphragm 78. The lower plate 82 is provided with a downwardly extending integral socket portion 86 which is internally threaded, as at 87, for receiving the upper threaded end of the connecting rod 50. A nut 88 limits the amount of insertion of said threaded rod end into the socket 87 and also serves to hold the rod and socket portion against separation.

In order to give lateral stability to the dia-

phragms 63 and 78, pairs of spring arms 89 and 90 are connected, respectively, between the circular plate 62 and the ring 68 and between the circular plate 82 and the ring 79. In the case of the pair of springs 89, the outer ends of said springs are secured by means of bolts 91 to the ring 68 and the inner ends are secured to the circular plate 62 by means of bolts 92. In the case of the lower pair of springs 90, the outer ends of said springs are bolted to the ring 79 by means of bolts 93 and to the circular plate 82 by means of bolts 94.

Each pair of springs 89 and 90 comprises relatively thin, flat, elongated strips of an elastic material, such as the laminated plastic material known as "Micarta." The springs are very stable laterally but are at the same time very flexible in the direction of movement of the diaphragms. If the diaphragms were made rigid laterally, they would also have to be rigid in their direction of movement, which is something that is not desirable. The main purpose of the diaphragm units is to have the units act as a cushion, a thing that is possible through the use of a compressible gas such as air.

The lower casing member 76 forms with the diaphragm 78 a chamber 95, into which air or other compressible gas is introduced through a pipe 96. In usual practice air is the gaseous fluid used in the diaphragm chambers 70 and 95. Compressed air from a suitable source is conducted through a pipe line 97 to branch lines 97a and 97b for admission through the pipes 71 or 96 into the diaphragm chambers 70 or 95. Reducing valves 98a and 98b in said branch lines 97a and 97b serve to regulate the air pressure in said chambers to the desired amount, which may be indicated by pressure gauges 99a and 99b.

Where it is desired to apply an additional loading pressure at the nip between the rolls 39 and 40, above that supplied by the weight of roll 40, the air pressure in the chamber 70 is brought up to the desired amount, and then the jack 51 is operated to bring the top roll 40 into contact with the bottom roll 39. Thereafter, the jack 51 is further operated so that the mechanism is in its mid-position as shown in Fig. 4, namely with clearance between the abutments 72 and 73 and between the abutments 84 and 85.

Such mid-positioning of the diaphragm mechanism is determined when a pointer 100 (Fig. 2) registers with the bottom face of an adjustable collar 100a. The collar 100a is movable along the rod 54 into its properly adjusted position where it is held by means of a set screw 100b. When the pointer 100 is opposite the lower face of the collar 100a, the diaphragm pressure mechanism will be in its normal position as illustrated in Figure 4. When in this position, the pre-determined air pressure within the chamber 70 will automatically determine the nip loading pressure between the press rolls 39 and 40.

In some instances, it may be desirable to reduce the nip pressure between the pressure rolls 39 and 40 below that produced by the weight of the top roll 40. In that case air is admitted under pressure into the chamber 95 to build up the desired pressure therein to offset a portion of the weight of the top roll 40, and thus obtain the required nip pressure. The jack 51 is then operated to bring the diaphragm pressure mechanism into mid-position again.

The abutments 72 and 73 and 84 and 85 provide stops that limit the relative movements of

the diaphragms 63 and 78 toward the bottoms of their respective casing members 67 and 76. The diaphragms 63 and 78 are, of course, prevented from being blown up like balloons by the fact that the straps 48a and 48b, held together as they are by the rods 48c and 48d, limit the outward movements of said diaphragms.

When the diaphragm pressure mechanism is brought into its mid-position, as previously described, the applied nip loading pressure between the rolls 39 and 40 is solely that due to the air pressure within the chambers 70 or 95. In that position, the end of each loading arm 41 is maintained in a floating state between the air cushions 18 within said diaphragm chambers. There is thus produced a very constant and uniform, as well as a resiliently applied, loading pressure at the nip between said rolls 39 and 40. Should the amount of pressure change for any reason, the operator can determine that visually by inspection of the indicating gauge 99a or 99b.

Referring now to the gaseous fluid pressure controlled mechanism for controlling the nip pressure between the pressure transfer roll 31 and the drier drum 10, said roll 31 is supported from one end of a pressure transmitting rocker arm 101. There are two such arms 101, one at each side of the machine for supporting the respective ends of the roll 31. Each of said arms 101 is pivoted intermediate its ends, as at 102, from the upright frame member 12. The outer end 103 of each of said rocker arms 101 carries a bearing housing 104, in which one of the ends of the rolls 31 is journalled. Each of said end bearing housings 104 carries a dependent arm 105 for journaling one end of the felt guide roll 30.

The other ends of the rocker arms 101 are connected to the diaphragm mechanisms TM. Said mechanisms, as best shown in Figures 1, 5, 6 and 7, are connected by depending rods 106 to jacks 107. The jacks 107 are similar in operation to the jacks 51, previously described. They may be either manually operated, as by means of handles 108, or power operated, and serve to raise or lower the rods 106. The jacks 107 are supported from the horizontal side frame member 15 on either side of the machine.

The lower end of each of the rods 106 is secured in a socket 109 (Figs. 5 and 6) of an upper casing member 110. Said casing member 110 is provided with a lower annular flange 111, to which is peripherally clamped a diaphragm 112 by means of a ring 113 and screws 114. The central portion of the diaphragm 112 is clamped between a small diameter upper circular plate 115 and the enlarged upper disk-like face 116 of a hollow cylindrical member 117. Screws 118 extend through said upper circular plate 115, the diaphragm 112 and into the upper enlarged walls 119 of the member 117. The lower cylindrical portion of said member 117 is swivelly secured in an end socket 120 carried by the free end of the rocker arm 101.

A pair of flat springs 121, similar to the flat springs previously described, are secured to the ring 113 by means of bolts 122 and to the underside of the circular plate 116, as by means of bolts 123. The casing member 110 and diaphragm 112 provide a chamber 124, into which a gaseous fluid under pressure may be admitted through a pipe 125.

The upper inner wall of the casing member 110 is provided with an abutment 126 to serve as a stop for limiting the movement thereagainst of the upper circular plate 115.

The ring 113 is provided along diametrically opposed portions of its arc with a downwardly and inwardly directed flange 127 which serves to limit the downward movement of the plate 116. The ring 113 (Fig. 7) is also provided with an integral, laterally extending arm 128, from the end of which depends a reference pin 129. Said reference pin 129 has a threaded upper end 130, which is threaded through said arm 128 and held in place therein by means of a nut 131.

An upwardly flanged plate 132 is fixedly mounted upon the cylindrical member 117 beneath the diaphragm. Said plate 132 is of such diameter that its upwardly turned annular flange 133 lies in spaced relationship to the ring 113. As illustrated in Figure 7, said flange 133 has a pointed projection 134 that serves as a reference for the lower edge of the pin 129. When said lower pin edge and pointed projection 134 are in registration, as illustrated in Figure 7, the diaphragm 112 is then in its normal, or mid-position.

As shown in Figures 1, 5 and 6, the casing member 110 is cocked with respect to the horizontal. This is due to the fact that there is a certain amount of angular movement between the upper and lower portions of the diaphragm mechanism when the pressure roll 31 is moved. As the pressure roll is lowered, the diaphragm tends to cock the other way and it goes from this cocked position, as illustrated in Figure 1, to a neutral position and then is cocked over the other way after the pressure roll has been lowered the full amount. The purpose of initially cocking the parts is to bend the diaphragm one-half of the total amount each side of its normal center line.

As previously described, air is introduced through the pipe 125 into the chamber 124 under the desired pressure, and then the jack 107 is operated to bring the pressure roll 31 up against the drier drum 10. This lift is continued until the diaphragm 112 comes to its mid- or normal position and the pressure roll pressure is controlled by means of air. In this way the full flexibility of the diaphragm under air pressure is realized for the actual loading of the pressure roll at the nip between said pressure roll and the drum 10.

As illustrated, the pressure transfer roll 31 is a suction roll, being connected to a suitable source of vacuum by means of an exhaust conduit 140. The position of the suction chamber within said roll 31 is indicated in dotted lines at 141 (Fig. 1).

In the gaseous fluid actuated diaphragm mechanism indicated at M (Fig. 1), the upper press roll 22 is suspended by means of brackets 142 from the under sides of a pair of pivotally mounted arms 143. Each of said arms 143 is pivoted, as at 144 to the lower end of a bracket 145, which, in turn, is suspended from the horizontal side frame member 15. The free end of each arm 143 is pivotally connected, as at 146 to a rod 147 that connects to a diaphragm unit 148.

The diaphragm unit 148 is of somewhat different construction from that already described. In this case the casing of the diaphragm unit 148 is connected by means of U-shaped arms 149 to the upper end of the screw 150 of a manually operable jack 151. As in the previous unit, the diaphragm of the unit 148 is pre-loaded by the introduction of air into the diaphragm chamber under the desired pressure, and the jack 151 is operated until the diaphragm assumes its normal position. In this way, the desired loading pressure is applied at the nip between the rolls 22 and 23.

It will thus be apparent that in all the various forms of my invention, I impose the desired amount of loading pressure upon the diaphragm and then operate the mechanically actuated jack, or other pressure-applying means, to bring the diaphragm into its normal or mid-position, at which the loading pressure is transmitted to the nip between the pressure rolls. I thus utilize the full flexibility of the diaphragm with a sufficient air pressure for the actual loading of the pressure rolls.

The stop provided by the abutment 126 and plate 115 prevents the pressure roll 31 from dropping more than a slight distance if the pressure on the diaphragm should drop or the diaphragm break. On the other hand the stop provided by the flanges 127 for the plate 116 prevents the diaphragm from being blown up like a balloon and broken by air pressure when the screw device 107 is operated to drop the pressure roll 31 away from the drier drum 10.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

- 30 1. A diaphragm unit comprising a concave casing having an annular flange, an annular clamping ring secured to said casing flange, a diaphragm clamped at its periphery between said flange and said ring to form with said casing a gas pressure chamber, rigid circular members holding the central portion of said diaphragm clamped therebetween and cantilever springs extending generally parallel to the normal plane of said diaphragm and having one end secured to one of said circular members and the other end secured to said clamping ring to impart lateral stability to said unit without substantially resisting axial movement of said diaphragm.
- 35 2. A diaphragm unit comprising a casing for connection to a force applying member, said casing having an annular peripheral flange, an annular clamping ring secured to said casing flange, a diaphragm having its periphery confined between said flange and said ring for cooperation with said casing to provide therewith a gas pressure chamber, means for introducing into said chamber a gas under pressure, rigid means clamping the central portion of said diaphragm and adapted to be connected to a force transmitting member, flat springs resiliently connecting said rigid clamping means to said casing flange and ring assembly and extending substantially parallel to each other end to said diaphragm to impart lateral stability of said unit without substantially resisting axial movement of said diaphragm, said diaphragm lying in the plane of said casing flange and said springs being adapted for flexing movement only in the plane of movement of said diaphragm to retain the parallel relationship between said diaphragm and said springs, and stop means carried by said casing for movement therewith and contacting said rigid means for limiting the axial movement of said diaphragm in either direction.
- 40 3. A diaphragm unit comprising a casing for connection to a force applying member, a diaphragm clamped to said casing to provide therewith a gas pressure chamber, means for introducing into said chamber a gas under pressure, rigid

means clamping the central portion of said diaphragm and adapted to be connected to a force transmitting member, resilient cantilever springs deflectable only in the direction of axial movement of said diaphragm connecting said clamping means to said casing and extending substantially parallel to each other and to said diaphragm to impart lateral stability to said unit without substantially resisting axial movement of said diaphragm, and means indicating the normal position of said diaphragm when applied transmitted forces are balanced by the desired amount of gas pressure within said chamber, said last-mentioned means including a reference member fixed to said rigid means and an indicating finger carried by said casing for movement therewith into alignment with said reference member when said forces are balanced.

4. A diaphragm unit comprising a concave circular casing having an annular flange, an annular clamping ring secured to said casing flange, a circular diaphragm clamped at its periphery between said flange and said ring to form with said casing a gas pressure chamber, a rigid circular member backing the central portion of said diaphragm to leave a narrow unbacked annular diaphragm portion and laterally rigid, axially deflectable members lying on either side of the center of said backing plate and extending generally parallel to each other and to the normal plane of said diaphragm and having one end secured to said circular member and the other end secured to said clamping ring to impart lateral stability to said unit without substantially resisting axial movement of said diaphragm.

5. A diaphragm unit comprising a concave casing having an annular flange, an annular clamping ring secured to said casing flange, a diaphragm clamped at its periphery between said flange and said ring to form with said casing a

gas pressure chamber, rigid circular members holding the central portion of said diaphragm clamped therebetween and cantilever springs comprising relatively thin and wide strips of laminated plastic material, each of said cantilever springs extending generally parallel to the normal plane of said diaphragm and each being connected at one end to said annular clamping ring and at the other end to one of said circular members to impart lateral stability to said unit without substantially resisting axial movement of said diaphragm.
